METHOD AND APPARATUS FOR AGGLOMERATING FINELY DIVIDED SOLID MATERIAL

Ira H. Wynne, Duluth, Minn., assignor to Oglebay, Norton and Company, Cleveland, Ohio, a corporation of Delaware

Application March 27, 1952, Serial No. 278,777

12 Claims. (Cl. 18—1)

This invention relates to a method and apparatus for use in agglomerating finely divided solid material and, more particularly, to a procedure and apparatus for forming such material into pellets or balls.

It is frequently necessary to agglomerate finely divided material into larger size particles or pellets. For example, iron ore concentrates, flue dust, and the like, cannot be utilized as a substantial part of the charge of a blast furnace until they have been formed into lumps or pellets many times the size of the individual particles thereof. One convenient mode of agglomerating or pelletizing materials of this nature is to roll or tumble them in a drum or cylinder while in a moist state, thereby forming ball-like bodies which, in the case of ore concentrates or the like, may be subsequently hardened by heating. In conventional apparatus and procedures of this nature, however, difficulties have been encountered in attempting to produce balls of desired size and having the requisite strength for the necessary handling preceding the hardening operation.

An object of this invention is to provide an improved method and apparatus for forming ball-like bodies from finely divided material, and, while not limited thereto, is especially useful for agglomerating fine ore particles, such as iron ore concentrates or the like, into pellets or balls of desired diameter and having sufficient strength prior to hardening to withstand handling such as sizing by screening and transportation by conveyors.

Another object of the invention is to provide an improved method and apparatus for forming ball-like bodies from finely divided material characterized by the introduction of the material into the interior of a rotating cylindrical member having its axis disposed substantially horizontally and the inner surface thereof formed with helical grooves so that the said material is subjected to complex rolling and/or tumbling motions with the result that the material is formed into compact ball-like bodies.

A further object of the invention is to provide a method and apparatus for forming and maintaining the aforementioned grooved surface on the interior of the cylindrical member.

An additional object of the invention is to provide an improved apparatus for forming ball-like bodies comprising a rotating cylindrical member or drum disposed in a substantially horizontal position and provided with a helical scraper with the said cylinder and scraper revolving in opposite directions at different speeds so that a part of the material to be formed into balls adheres to the inner wall of the cylinder and is scraped into substantially helical grooves while the remaining material rolls and/or tumbles thereover in a complex motion productive of compact ball-like bodies.

The invention also has as an object thereof the provision of a method and apparatus for forming ball-like bodies from finely divided material as defined above and in which the formed bodies are accelerated towards the discharge end of the cylindrical member in which they are formed.

2

The invention further resides in certain novel steps of procedure and in the combination and arrangement of parts of the apparatus, and hence further objects and advantages of the invention will be apparent to those skilled in the art to which it pertains from the following description of the present preferred embodiment, described with reference to the accompanying drawings in which:

Fig. 1 is a longitudinal sectional view taken through the present preferred embodiment of a balling apparatus constructed in accordance with this invention and capable of performing the method thereof, certain parts of the apparatus being shown in elevation and others broken away for the sake of clarity of illustration.

Fig. 2 is a top plan view of the balling apparatus shown in Fig. 1.

Fig. 3 is an end elevational view of the inlet end of the balling drum or cylinder as seen from the right-hand side of Figs. 1 and 2; and

Fig. 4 is a fragmentary, enlarged, sectional view taken through a portion of the side wall of the balling cylinder or drum substantially on the line 4—4 of Fig. 1 and illustrating the novel nature of the interior surface of the apparatus.

The apparatus of this invention, and which is employed in performing the novel method of agglomerating finely divided solid material, comprises a hollow cylindrical member or drum, generally designated 10, preferably formed of metal plates suitably secured together with the length of the drum or cylinder being greater than the diameter thereof. This drum or cylinder is supported for rotation, with its longitudinal axis extending substantially horizontally, by means of a pair of circular tracks or rails 11 and 12 secured to the external surface of the cylindrical member or drum in spaced relationship and each supported upon spaced pairs of flanged wheels such as 13 and 14, see Figs. 1 and 3. The tracks 11 and 12 may be in the form of I-beams or other structural members having cross sections similar to railroad rails while the pairs of wheels 13 and 14 are preferably flanged similar to the wheels employed upon the trucks of railroad vehicles. The pairs of wheels 13 and 14 are disposed so that each of the individual wheels of a pair thereof is at either side of the vertical center line of the cylinder or drum, thereby providing a cradle-like support.

Endwise movement of the drum or cylinder 10 may be prevented by oppositely disposing the flanges of the pairs of wheels 13 and 14, but, as herein shown, a more positive prevention of such endwise movement is provided by a pair of thrust rollers or wheels 15 and 16, positioned to engage opposite sides of one of the rail or track members such as 12. As shown in Fig. 1, these thrust rollers or wheels 15 and 16 are rotatably supported on suitable bearings or brackets, such as 17 and 18, with the axes of the rollers approximately vertical.

The bearings for the flanged wheels 13, 14 and the bracket or bearing members 17, 18 are mounted upon suitably interconnected structural steel members to provide a base frame, generally designated 19, which is in turn supported upon a floor or structural members, generally designated 20. As mentioned heretofore, the axis of the cylindrical member or drum 10 is disposed substantially horizontally but this axis may be tilted slightly from the horizontal by any suitable means. For example, such tilting of the cylinder or drum may be effected by raising one end of the base frame 19 relative to the supporting structure or floor 20. As indicated in Fig. 1, the forward or left-hand portion of the base frame 19 is bolted to the floor or supporting means 20, as indicated at 21, while the rear or right-hand portion of the frame

member 19 is provided with screw and nut assemblies 22 and 23 by which this portion of the frame 19 may be elevated relative to the floor or support 20 and thereby provide a slight inclination of the cylinder or drum towards the discharge end which is at the left, as viewed in Fig. 1. The nut and bolt assemblies 22 may be in the form of jack screws or may be simply hold-down bolts with the desired elevation being effected by loosening them and the bolts 21 and then inserting wedges, shims, or the like, between the frame 19 and the support or floor 20.

Intermediate the tracks 11 and 12, the cylinder or drum 10 is provided with a ring gear 24 which meshes with a driving gear 25, disposed at one side of and adjacent the bottom of the drum or cylinder, see Fig. 2. The gear 25 is driven by a variable speed electric motor 26 through a flexible drive which may comprise V-belts or chains 27, connected with the input shaft of a conventional speed reduction unit 28, the output shaft of which is connected with the aforementioned driving gear 25. Consequently, the drum or cylinder 10 may be driven at a speed determined by the speed of the motor and the rate of reduction provided by the unit 28.

The material which is to be processed within the cylinder or drum 10 is supplied thereto by a suitable conveying means as, for example, an endless belt 29, the head pulley of which is supported by a beam 30 and which is in turn supported by structural steel members 31 and 32 rising from the base or frame 19 and connected at their tops by the transverse member 33, see Fig. 3. The conveyor 29 may be provided with a cleaning or scraping means such as a blade 34 which is urged into engagement with the surface of the conveyor belt by a counter-weighted pivoted arm 35, see Fig. 1. The finely divided material which is to be processed into ball-like bodies is supplied to the conveyor 29 in any suitable manner not forming a part of this invention and is carried thereby into the balling cylinder or drum 10 adjacent the entrance end thereof, which is the right-hand end as viewed in Figs. 1 and 2 of the drawings. Any material tending to adhere to the conveyor belt 29 due to the moist condition of the material is removed therefrom by the scraper 34.

In order to prevent material falling from the entrance of the cylinder or drum, the latter is provided with an end wall or closure plate, designated 36, which is substantially disc shaped and is stationarily supported on the aforementioned structural members 30, 31, 32 and 33, an opening being provided in the closure plate or member 36 through which the head pulley of the conveyor 29 projects as will be apparent from Figs. 1 and 3 of the drawings. The diameter of the closure plate or member 36 is less than the internal diameter of the drum 10 to prevent binding therebetween and the drum or cylinder 10 is provided with a circumferentially extending flange 37 of angular cross section, one leg of which is secured to the drum or cylinder and the other leg of which overlies the outer surface of the stationary closure plate 36.

The interior surface of a cylindrical member or drum formed of curved metal plates is relatively smooth and hence frequently does not provide satisfactory balling of the finely divided material introduced therein. This is due to a number of causes, one of which is the fact that, although the material in moist condition tends to adhere to the interior surface of the rotating cylindrical member, portions thereof fall therefrom in chunks of various sizes and of widely varying weights. These lumps or chunks tend to roll into large loosely compacted balls, which pass from the balling member or drum soon after the material of which they are composed is detached from the wall of the cylindrical member. Such bodies are undesirable not only because of their size but also because they have not been rolled or tumbled about sufficiently to compact them and provide the necessary "green strength" to withstand subsequent handling prior to indurating. In an effort to overcome this condition, various expedients

such as scrapers and the like have been tried, and, while these generally produce improved results, they do not always provide the necessary retention time of the material within the balling cylinder or drum so that a large portion of the material must be re-circulated by collecting the under and over-sized discharge from the cylindrical member or drum and conveying this material back to the inlet to be re-introduced along with fresh material.

In accordance with this invention, highly improved 10 agglomeration of finely divided material into ball-like bodies is achieved by creating and maintaining a novel surface on the interior of the cylindrical member or drum. This cylindrical surface comprises multiple convolutions of helical grooves, the major portion of which are inclined 15 so that any loose material therein tends to move back towards the inlet of the cylinder or drum. In the preferred embodiment the inclination of the grooves adjacent the entrance and discharge ends of the cylinder or drum are reversely inclined, thereby accelerating the movement of 20 material in these portions of the cylindrical member or drum towards the discharge end. While these grooves may be formed by various means, they are preferably provided by producing an adhering layer of material upon the internal surface of the cylindrical member or drum 25 and then scraping this layer by a helical member rotating at a different speed and in a different direction from that of the rotation of the drum or cylinder. The aforementioned grooves of reverse inclination adjacent the ends of the drum or cylinder may be provided by having the 30 convolutions of the helical scraper adjacent the ends reversed relative to the convolutions on the main portion of the scraper.

The presently preferred method of forming the helically grooved surface within the cylindrical drum 10 is achieved 35 by first providing a roughened surface on the interior of the metal plates forming the side wall of the cylinder or drum. This roughened surface may be achieved by any suitable expedient but in the preferred embodiment is provided by attaching expanded metal 38 or the like to the inner surface of the cylindrical member or drum 10. Consequently, moist finely divided material introduced into a drum with such a surface will adhere thereto in a continuous layer. This layer is then formed into the aforementioned helically grooved configuration by a rotatable scraping means, generally designated 39.

The scraping means 39 comprises an elongated shaft 40 extending longitudinally through the cylindrical member or drum 10 and rotatably supported externally thereof by suitable bearings 41 and 42 carried respectively by the 45 aforementioned supporting member or beam 33 and a corresponding supporting member 43 which is located adjacent the discharge end of the drum and is connected with the supporting base 19 by downwardly and rearwardly extending members 44, see Fig. 1. Extending about the shaft 40 is a helically arranged scraping member 45 of the type similar to that frequently used for conveying material and known in the trade as a "ribbon-flight" conveyor, the scraper member being formed of a ribbon-like metal strip in helical configuration. The convolutions of the main portion of the scraper have the direction of a right-hand thread and are connected to the axle or shaft 40 at spaced points to provide a rigid construction. The main scraper portion terminates short of the discharge end of the cylinder or drum 10 and this portion of the cylinder is provided with a scraper portion 45a having the convolutions reversely disposed, but similarly connected with the shaft 40. Likewise, the main portion 45 of the scraper member terminates short of the closure plate 36 and a portion 45b is there provided similar to the portion 45a with the convolutions reversely disposed relative to the main portion; this portion 45b preferably being shorter than the portion 45a.

The shaft 40 extends beyond the bearing 41 externally of the closure plate 36 and the outer end of this shaft is 75 provided with a sprocket wheel 47 which is connected by

a chain 48 to a sprocket wheel 49, see Figs. 2 and 3. The sprocket wheel 49 is connected at one end of a shaft 50 which extends substantially parallel with the axis of the cylinder or drum 10 and is suitably supported upon the frame members which support the drum. The other end of the shaft 50 is provided with a sprocket wheel 51 which is connected by a chain 52 to a sprocket wheel 53 carried by or connected with the shaft on which the drum driving gear 25 is supported.

It will be apparent from the construction just described that the direction of rotation of the cylinder or drum 10 is reverse to that of the shaft 40 for the scraping means. Moreover, the sizes of the sprocket wheels are such that an increase of speed of the scraping means relative to that of the drum is provided and the relative speeds of the drum and scraping means, once determined, are maintained due to the positive drive provided by the sprocket wheels, chains and gears. Hence, variation of the speed of the motor 26 not only varies the speed of the drum or cylinder 10 but also correspondingly varies the speed of the scraping means 39. Preferably, the direction of rotation of the cylindrical member or drum 10 is counter-clockwise, as viewed from the entrance end of the drum as seen in Fig. 3, while the direction of rotation of the scraping means is clockwise when viewed from the same location. These directions are, of course, reversed when the drum is viewed from the discharge end.

The position of the helical scraping means is so located that the convolutions thereof cut helical grooves in the layer of material adhering to the expanded metal or the like on the interior of the cylinder or drum. In the preferred construction, the shaft of the scraping means is disposed to the right of the vertical center line of the cylinder or drum 10, as viewed from the inlet end, and on a plane extending at an angle of 45 degrees upon the horizontal central plane through the drum. The diameter of the scraping means and the position of its shaft 40 along the aforementioned inclined plane are such that the bottoms of the grooves cut in the material adhering to the side wall of the drum do not extend to the expanded metal or the like 38 which is provided on the interior of the drum, see Fig. 4.

Due to the aforementioned directions of relative rotation of the scraping means 39 and of the cylindrical member or drum 10, and also because of the hand of the convolutions of the several portions of the scraping means, helical grooves having configurations substantially similar to those shown in Fig. 1 will be formed during rotation of the drum and scraper. From this figure it will be seen that the major portion of the cylindrical member or drum has the grooves therein sloping downwardly to the right, that is, back towards the inlet end of the drum, while the grooves 55 adjacent the discharge end, as well as the grooves 56 immediately adjacent the inlet, slope in the opposite direction. Moreover, the regions intermediate the grooves 54 and the grooves 55, 56, where the direction of slope changes, are in the form of single circumferentially extending grooves 57 and 58. The surface thus formed within the cylindrical member may be protected from decrescence or deterioration by spraying the latter with waterglass or other material of similar nature, although this is not always necessary since the grooves are continuously re-defined during operation of the mechanism through the relative rotation of the drum and scraper.

After the grooved surface has been formed within the balling cylinder or drum 10, additional finely divided material introduced therein by the conveyor 29 will receive a complex rolling and/or tumbling movement which results in the formation of well compacted ball-like bodies of superior quality. The sizes of these bodies may be controlled by the speed of rotation of the drum, the moisture content of the material, and the inclination of the axis of the drum or cylinder 10. During this rolling and/or tumbling operation, the material forms first into relatively small nuclei or balls which are carried partly

around within the cylindrical member or drum by the aforementioned grooves. A part of this material tends to roll or slide downwardly within said grooves and hence be carried back towards the entrance of the drum while other portions of the material tend to adhere within the said grooves. Any such adhering material reaching the scraping means 39 will be crushed and/or scraped back into the drum for further rolling action. In general, the material will be carried partly around within the drum during its rotation, roll backwardly through the said grooves a part of the distance and then dropped over the outer edges into the next succeeding groove or grooves, thus progressing forwardly within the drum towards the discharge end, this progression being assisted, if necessary, by slightly inclining the axis of the drum or cylinder 10 towards the discharge end. The aforementioned tendency of the material to at least partially return towards the entrance of the drum, due to the inclination of the grooves 54, makes for a longer retention time of the ball-like bodies within the drum. This longer retention time, together with the movement of the bodies over the successive edges or ridges between the grooves provides an extremely compact form of the ball-like bodies so that by the time they have reached the discharge end of the drum they are generally in suitable form for transfer to an indurating furnace or other means of hardening and/or further treating the bodies.

As the ball-like bodies approach the discharge end of the cylindrical member or drum they enter the portion of this member which has the helical grooves 55 sloping in the opposite direction from the grooves 54 of the main body of the drum with the result that the bodies are accelerated in their movement toward the discharge end of the drum, thus facilitating their transfer therefrom and preventing injury thereto by continued rotation within the drum and striking against other bodies. Any material which may be of a size less than that desired is removed from the material discharging from the drum by a screening means 59 which is substantially frusto-conical in shape and is formed by spaced angularly disposed rods 60 of stainless steel or the like welded to a reinforcing ring or rings such as 61, thereby providing a unitary structure which is bolted or otherwise secured to the cylinder or drum 10 adjacent the discharge end. The inclination of the separate rods or bars of the screening means is in the same general direction as that of the grooves 55 thereby facilitating discharge of the bodies.

The material thus discharged from the cylindrical member or drum 10 is therefore classified according to size by the screening means 59 with the bodies equal to or larger than the selected size, corresponding to the openings in the screen, being transferred to a further treatment while the bodies and fragments thereof of lesser size fall through the openings between the bars 60 of the screening means and are conveyed by suitable means back to the entrance to the balling drum. This separate disposal of the product from the cylindrical member or drum may be effected by separate conveyors, but in the form shown in the drawings a single conveyor 62 is provided which is of the belt type having an integral rib or ridge 63 extending longitudinally therealong substantially medially so as to provide, in effect, two separate compartments. The said ridge or dividing portion 63 is disposed substantially under the outer edge of the screening means 59 so that the ball-like bodies of size equal to or greater than the openings between the bars 60 are received to the left of that ridge, as shown in Fig. 1, while the smaller sized bodies and fragments thereof drop upon a portion of the conveyor to the right of the said ridge. A suitable stop or diverting member 64 may be provided in front of the discharge end of the drum to prevent the ball-like bodies from being impelled beyond the edge of the conveyor 63. This stop means may comprise a vertically extending plate faced with flexible material, the lower end 75 of which rides upon the upper surface of the conveyor 62.

The discharge end of the conveyor 62 is positioned over two oppositely running conveyors 65 and 66 so that the ball-like bodies of proper size are deposited upon one conveyor, such as 65, for travel to a suitable hardening furnace or the like, while the bodies and fragments thereof of smaller size drop upon the conveyor 66 and are carried in the opposite direction back, by means not shown, to the entrance of the balling drum for re-circulation therethrough. It should be noted, however, that by virtue of the novel construction and method of balling here disclosed that quantity of material needed to be re-circulated is considerably less than that provided by prior structures.

As has been mentioned heretofore, the helical grooves 56 adjacent the inlet portion of the balling cylinder or drum have an inclination or slope reverse to the grooves 54 in the main portion of the drum. This assists in directing the material away from the end plate 36 and into the main portion of the cylindrical member or drum, thus not only preventing leakage of the material from the inlet end but also providing distribution of the material as it is initially charged into the cylinder by the conveyor 29. In addition to the forming of helical grooves by the scraper portion 45b, the outer end of this part of the scraping means may be shaped as indicated at 67 to provide a scraping action upon the adjacent inner face of the end plate 36, thus reducing the tendency of the finely divided material to work out of the cylindrical member or drum along the shaft 40.

The angle of the helical grooves 54, as measured from a vertically extending line, may be varied by varying the relative speed of the balling drum with respect to the speed of the helical scraping means. This may be effected by changing the sprocket 53 in the drive for the scraping means. Any change of this or of the other sprocket wheels which would result in a different relative speed between the drum and the scraping means will, of course, alter the grooves within the drum, and it will therefore be necessary to run the apparatus for a sufficient period of time to form the new grooves by cutting through the ridges between the previous grooves and building up the new ridges defining the new grooves. Therefore, where it appears that it may be necessary to change the angle of the helical grooves, it is preferable not to harden the surface after formation of the grooves to the extent that it would be difficult to alter by simply allowing the scraping means to cut new grooves. Where, however, the angularity of the grooves is to remain fixed for an appreciable length of time, the interior surface can be protected from decrescence to a greater extent, and in such instances it is even possible to form this helical surface of materials other than the material which is to be formed into the ball-like bodies within the cylinder or drum.

The relative dimensions of the parts of the apparatus will, of course, vary for different installations but the following dimensions may be mentioned by way of example to illustrate the nature of the grooved surfaces formed within the balling drum. Thus, a drum having a diameter of 7 feet may be provided on its inner surface with expanded metal after which finely divided moist iron ore concentrates, or other similar material which will adhere to the surface of the expanded metal and form a continuous layer thereon are introduced. The scraping means for such a cylinder or drum has the scraper portions or ribbon-like members 14" in diameter and of a 14" pitch throughout, but with the convolutions of the two end portions reversely disposed relative to those of the main portion. This scraping means is positioned so that the depth of the grooves formed is in the order of $\frac{3}{8}$ " and the thickness of the material in the depth of the grooves likewise in the order of $\frac{3}{8}$ ". When such a drum is rotated at ten revolutions a minute and the scraping means is rotated at 56 $\frac{2}{3}$ revolutions per minute, the helical angle of the grooves is 17° 7'. At the same speed of the drum but with the scraper rotating at 83 $\frac{1}{3}$ revolutions per minute, the helical angle is 24° 22'. The distance between ridges of the grooves is then in the order

of 4.67". The speed of a cylinder or drum of this character may be varied between 8 and 16 revolutions per minute if it is desired to alter the rate of the formation of the ball-like bodies and/or the size thereof. The speeds of the scraper means 39 will, of course, vary from those given above as the speed of the drum is varied, but the relationship of the speeds will remain in the same order so that the configuration of the helical grooves within the drum is not altered except by changing the sprocket wheel 53, as mentioned heretofore.

It is believed that the operation of the apparatus and the manner in which the method is performed will now be clearly apparent from the foregoing detailed description. However, it is desired to emphasize that when the grooved surface is formed of the finely divided material from which the ball-like bodies are formed the said grooved surface is continuously maintained by the action of the helical scraper upon the material continuously supplied to the cylinder or drum. However, this surface may be protected against decrescence by spraying with a suitable binder or adhesive and in some instances the surface can be formed of materials other than those which are to be agglomerated.

Although the method and apparatus of this invention have been illustrated and described in considerable detail as they are incorporated in a preferred embodiment, it will be understood that variations may be made in the structures and in the steps of the procedure by those skilled in the art after having had the advantages of this disclosure. Thus, the dimensions given for the drum and scraper may be varied from the values stated. Moreover, the grooved surface may in some instances be formed by scraping means other than the helical member shown. Also, in some instances, the cylinder or drum with the novel grooved surface may be employed to effect agglomeration without the need of a power driven scraper especially where the grooved surface is sufficiently protected from decrescence due to wearing away by abrasion, cracking, or other deterioration.

The above and other variations and adaptations of the invention are deemed properly encompassed within the ambit thereof and, consequently, the detailed description and illustrations of this application are not to be considered as limitations upon the invention except as may be required by the spirit and scope of the subjoined claims.

Having thus described the invention, I claim:

1. The method of producing ball-like bodies from finely divided material comprising introducing the material in a moist condition into the interior of a hollow rotating cylindrical member disposed with its axis extending substantially horizontally so that the said material tends to adhere to the inner surface of the cylindrical member as a continuous layer thereabout, scraping the said layer of material with a helical member rotating at a speed greater than the speed of the cylindrical member and in the opposite direction, thereby producing a helically grooved surface of multiple convolutions in the material adhering to the said cylindrical member, and continuing the introduction of the finely divided material into one end of said cylindrical member while rotating the latter and said helical member at the aforementioned relative speeds so that the said finely divided material receives a complex rolling action upon said surface resulting in the formation of ball-like bodies which roll towards the other end of said cylindrical member.

2. The method of producing ball-like bodies from finely divided material comprising introducing the material in a moist condition into one end of a hollow cylindrical member disposed with its axis extending substantially horizontally so that the said material is distributed lengthwise of said member and adheres to the inner surface of the cylindrical member as a continuous layer thereabout, scraping the said layer of material with a helical member rotating at a speed greater than the

speed of the cylindrical member and in the opposite direction with the hand of the helical member being such that it produces a helically grooved surface of multiple convolutions in the material adhering to the said cylindrical member with the grooves thereof sloping towards the end at which the finely divided material is introduced, and continuing the introduction of said material while rotating the cylindrical member and said helical scraping member at the aforementioned relative speeds so that the said finely divided material receives a complex rolling action upon said surface resulting in the formation of ball-like bodies which roll towards the end of said cylindrical member opposite that into which the material was introduced.

3. The method as defined in claim 2 and further comprising accelerating the discharge of the formed bodies from the said cylindrical member by providing the said grooves in the inner surface thereof adjacent the discharge end with a slope in the opposite direction to that of the slope of said grooves intermediate the ends of the cylindrical member.

4. The method of producing ball-like bodies from finely divided material comprising introducing a quantity of the material in a moist condition into the interior of a hollow rotating cylinder disposed with its axis extending substantially horizontally so that the said material tends to adhere to the inner surface of the cylinder as a continuous layer thereabout, scraping the said layer of material with a helical member rotating at a speed greater than the speed of the cylinder and in the opposite direction thereby producing a helically grooved surface of multiple convolutions in the material adhering to the said cylinder, spraying the said grooved surface with a substance preventing decrescence of the said surface, and thereafter introducing further quantities of the finely divided material into one end of said cylinder while rotating the latter and said helical scraping member at the aforementioned speeds so that the said finely divided material receives a complex rolling action upon said surface resulting in the formation of ball-like bodies which roll towards the other end of said cylinder.

5. The method of producing ball-like bodies from finely divided material comprising introducing a quantity of the material in a moist condition into the interior of a hollow rotating cylinder disposed with its axis extending substantially horizontally so that the said material tends to adhere to the inner surface of the cylinder as a continuous layer thereabout, scraping the said layer of material with a helical member rotating at a speed greater than the speed of the cylinder and in the opposite direction with the hand of the helical member being such that it produces a helically grooved surface of multiple convolutions in the material adhering to the said cylinder with the majority of the grooves thereof sloping towards one end of the cylinder, spraying the said grooved surface with a substance preventing decrescence of the said surface, and thereafter introducing further quantities of the finely divided material into one end of said cylinder while rotating the latter and said helical scraping member at the aforementioned relative speeds so that the said finely divided material receives a complex rolling action upon said surface resulting in the formation of ball-like bodies which roll towards the other end of said cylinder.

6. An apparatus of the character described for producing ball-like bodies from finely divided material comprising a hollow cylinder rotatably supported with its axis extending substantially horizontally, means adjacent one end of said cylinder to introduce finely divided material into the interior thereof, means to rotate said cylinder, a helical scraping means rotatably supported adjacent the inner surface of said cylinder and adapted to engage and scrape material adhering to the said inner surface, and means to rotate said scraping means in a reverse direction to that of the cylinder rotation and at a faster speed than the speed of the cylinder thereby producing helical

grooves in the material adhering to the interior of the cylinder, whereby the finely divided material not adhering to the cylinder has a complex rolling motion imparted thereto resulting in production of ball-like bodies which are discharged from the other end of said cylinder.

7. An apparatus as defined in claim 6 wherein the convolutions of the said helical scraping means adjacent either end thereof are reversed relative to the convolutions intermediate the ends.

10 8. An apparatus as defined in claim 6 wherein the said cylinder and scraping means are rotated by a common source of power with a positive driving means between said cylinder and scraping means to thereby maintain a predetermined timed relationship of their speeds of rotation.

20 9. An apparatus of the character described for producing ball-like bodies from finely divided material comprising a drum rotatably supported with its axis extending substantially horizontally, means adjacent one end of said drum to introduce finely divided material into the interior thereof, means to rotate said drum, a helical scraping means extending through said drum adjacent the inner surface of the latter and adapted to engage and scrape material adhering to the said inner surface, means externally 25 of said drum rotatably supporting said scraping means, positive drive means interconnecting the said scraping means and drum rotating means to effect rotation of the scraping means in reverse direction to that of the drum rotation and at a faster speed than the speed of the latter thereby producing helical grooves in the material adhering to the interior of the drum, whereby the finely divided material not adhering to the drum has a complex rolling motion imparted thereto resulting in production of ball-like bodies which are discharged from the end of the drum 30 opposite that into which the material was initially introduced.

35 10. An apparatus as defined in claim 9 wherein the convolutions of the said helical scraping means adjacent either end thereof are reversed relative to the convolutions intermediate the ends, and the convolutions intermediate the ends of the scraping means have a hand such that they produce grooves which slope towards the end of the drum into which the material is introduced while the reversed convolutions form grooves adjacent the ends 40 of the drum which slope towards the discharge end of the latter.

45 11. The method of producing a surface for the formation of ball-like bodies from finely divided material comprising introducing a portion of the finely divided material in a moist condition into the interior of a hollow rotating cylindrical member disposed with its axis extending substantially horizontally so that the said material tends to adhere to the inner surface of the member as a continuous layer thereabout, and scraping the said layer 50 in a manner producing a plurality of helical grooves substantially throughout the length of said layer and sloping towards the entrance end of said cylindrical member, whereby the continued introduction of finely divided material into the entrance end of said cylindrical member while rotating the latter and continuing the said scraping action results in the additionally introduced material receiving a complex rolling action upon the grooved surface thereby forming ball-like bodies.

55 12. The method of producing a surface for the formation of ball-like bodies from finely divided material comprising introducing a portion of the finely divided material in a moist condition into the interior of a hollow rotating cylindrical member disposed with its axis extending substantially horizontally so that the said material tends to adhere to the inner surface of the cylindrical member as a continuous layer thereabout, scraping the said layer of material with a helical member rotating at a speed greater than the speed of the cylindrical member and in the opposite direction thereby producing a helically 60 grooved surface of multiple convolutions in the material

11

adhering to the said cylindrical member, and continuing the introduction of the finely divided material into one end of said cylindrical member while rotating the latter and said helical member at the aforementioned relative speeds, whereby a part of the additionally introduced material maintains the said grooved surface and the remainder together with the material detached from said surface receives a complex rolling action upon said surface thereby forming ball-like bodies.
